UNITED STATES PATENT OFFICE.

GEORGE A. GAUTHIER, OF HARTFORD, CONNECTICUT, ASSIGNOR TO THE ARROW ELECTRIC COMPANY, OF HARTFORD, CONNECTICUT, A CORPORATION OF CONNECTICUT.

BINDING-POST.

1,142,416.

Specification of Letters Patent.

Patented June 8, 1915.

Application filed October 28, 1914. Serial No. 868,953.

To all whom it may concern:

Be it known that I, GEORGE A. GAUTHIER, a citizen of the United States, residing at Hartford, in the county of Hartford and State of Connecticut, have invented a new and useful Improvement in Binding-Posts, of which the following is a specification.

This invention relates to a binding post which is more particularly designed for and intended to be used in connection with rotary snap electric switches, for securing the ends of the conducting wires.

The object of the invention is to provide a binding post which is very cheap to make, simple to apply to a switch base and which is so shaped that the end of a circuit wire may be very easily and securely fastened in an approved manner.

Figure 1 of the accompanying drawings shows a front view of a binding post which embodies this invention, fastened to a section of the base of a snap switch. Fig. 2 shows a plan of the same. Fig. 3 is a view looking at one side. Fig. 4 is a view looking at the other side of the binding post.

The post has a back wall 1 which is provided with a threaded perforation for the binding screw 2. Projecting backwardly from the wall of the post shown, is a pole 3 which is designed to be engaged by the spring fingers of the movable part of the switch with which the binding post is used. Extending on each side of the back wall are ears 4 with threaded openings for the screws 5 which are used to fasten the binding post to the switch base 6. Extending forwardly from one side of the back wall and desirably somewhat oblique with relation to the plane of the top of the switch base is a wall 7 and, extending forwardly from the edge of the back wall on the other side of the binding screw is a lug 8.

The binding post is fastened to the switch base in such relation to the opening 9 in the base and through which the end of the circuit wire is passed, that a channel is formed in line with said opening for guiding the end of the wire when it is passed through the switch, this channel being bounded by the back wall, the forwardly projecting wall on one side, the shank of the screw on the other side and the head of the screw at the front. Snap switches are placed against the surface of a wall, and with binding posts formed with such channels as described, the

switches may be easily thrust onto the ends of the circuit wires and set back against the surface of the wall and fastened in position with the ends of the wires passing through the channels in position to be secured. After the switch base has been put into place and onto the ends of the circuit in the manner stated the bared ends of the wires are bent over and backward and snapped under the lugs and back of the heads of the screws. Then when the screws are tightened the bared ends of the conducting wires, which are thus easily located, will be clamped against the back wall of the binding posts and prevented from squeezing out from under the screw heads by the side walls on one side and the lugs on the other. Thus, with this construction the ends of the wires are readily engaged with the binding posts and tightly and securely clamped by the binding screws.

The invention claimed is:—

1. A binding post for a snap switch having a back wall, a binding screw turning in a threaded opening in the back wall, ears with perforated openings for securing the binding post in place, a wall projecting forwardly from the back wall and in conjunction with the binding screw forming a channel adapted to facilitate the location of the end of a circuit wire and aid in securing the wire in place, and a lug projecting forwardly from the back wall of the post on the other side of the screw from the side wall and in conjunction with the screw forming an additional means for holding the end of the circuit wire securely in place when the binding screw is turned in.

2. A binding post for a snap switch having a back wall with a threaded opening, a binding screw turning in said threaded opening in the back wall, a contact plate extending backwardly from the back wall, attachment ears extending outward from the sides of the back wall, a side wall extending forward from the back wall on one side of the screw and a lug extending forward from the back wall on the other side of the screw.

3. A binding post for a snap switch having a back wall, a binding screw turning in said back wall, attachment ears extending from the sides of the back wall, a side wall extending forwardly from the back wall and obliquely with relation to the plane of the bottom of the binding post, and a lug ex-

tending forwardly from the back wall on the other side of the binding screw from the side wall.

4. The combination with the base of a snap switch having an opening for the passage of a circuit wire, of a binding post having a back wall that is back of said opening, a side wall that is at one side of said opening, a binding screw, turning in the back wall and having its shank in line with the other side of said opening, and a lug projecting forward from the back wall of the binding post on the side of the screw opposite from the side wall.
5. A binding post for a snap switch having a back wall with a threaded opening, a binding screw turning in said opening in the back wall, perforated attachment ears extending outward on the sides at the bottom, a side wall extending forward from the

back wall on one side of the screw, and a lug extending forward from the back wall on the other side of the screw.

6. The combination with the base of a snap switch having an opening for the passage of a circuit wire, of a binding post having a wall forming one side of a continuation of said opening, a wall that forms another side of a continuation of said opening, a binding screw turning in one of said walls and having its shank forming a third side and its head forming a fourth side of said continuation of said opening, and a lug projecting forward from the wall carrying the screw on the opposite side of the screw from the other wall.

GEORGE A. GAUTHIER.
